United States Patent Office

Des. 220,696
Patented May 11, 1971

220,696

CONTROL ENCLOSURE

Stephen Lazzo III, Park Forest, Ill., assignor to
General Electric Company

Filed Oct. 24, 1969, Ser. No. 19,700

Term of patent 14 years

Int. Cl. D13—03

U.S. Cl. D26—13

FIG. 2

FIG. 3

FIG. 4

FIG. 1

FIG. 5

FIG. 1 is a front perspective view of a control enclosure showing my new design;

FIG. 2 is a side elevational view of one side thereof;

FIG. 3 is a front elevational view thereof;

FIG. 4 is a side elevational view of the other side thereof; and

FIG. 5 is an end elevational view thereof.

I claim:

The ornamental design for a control enclosure, substantially as shown.
